(57) **CLAIM**

The ornamental design for a staking system for growing container, as shown and described.

DESCRIPTION

FIG. 1 is a front view showing a staking system for growing container, the rear view being a mirror image thereof;

FIG. 2 is a right side view thereof, the left side view being a mirror image thereof; and,

FIG. 3 is a perspective top front, and left side view thereof.

The broken lines in FIG. 1–3 showing a growing container are for the purpose of illustrating the environment of use of the design and form no part of the claimed design.
